HEDDLE BARPOST

John M. Sample and Joseph E. Blanchard, Millbury, Mass., assignors to Watson-Williams Manufacturing Company, Millbury, Mass., a corporation of Massachusetts

Application December 5, 1940, Serial No. 368,678

3 Claims. (Cl. 139—92)

This invention relates to loom harness frames and particularly to harness frames in which steel heddles are used. Such heddles are mounted on upper and lower heddle bars which extend the full width of the harness frame and which are commonly supported at both ends in the side members of the frame.

In relatively wide harness frames, it is desirable to additionally support the heddle bars at one or more intermediate points, commonly by heddle bar posts fixed in the top and bottom harness frame members and detachably engaging the heddle bars.

It is the general object of our invention to improve and simplify the construction of such heddle bar posts and particularly to avoid the use of relatively movable parts, while at the same time providing for convenient attachment of the bar to the post or detachment of the bar therefrom.

Our invention further relates to arrangements and combinations of parts which will be herein-after described and more particularly pointed out in the appended claims.

A preferred form of the invention is shown in the drawing, in which

Fig. 1 is a partial front elevation of a harness frame embodying our improvements;

Fig. 2 is an enlarged front elevation of certain parts shown in Fig. 1;

Fig. 3 is a sectional side elevation, taken along the line 3—3 in Fig. 2;

Fig. 4 is a side view of a stud forming one part of our improved heddle bar post;

Fig. 5 is a front view, looking in the direction of the arrow 5 in Fig. 4;

Fig. 6 is a front elevation of a blank for a spring member;

Fig. 7 is a front elevation of the spring member in final form; and

Fig. 8 is a side elevation, looking in the direction of the arrow 8 in Fig. 7.

Referring to the drawing, we have shown in Fig. 1 parts of a loom harness frame including a bottom frame member 10, side frame members 11, a heddle bar 12, and a heddle bar post P. All of these parts except the post P are of usual commercial construction, and the ends of the heddle bar 12 are to be secured in the two side members 11 in the usual manner.

The post P comprises a stud 20 (Fig. 4) having a screw-threaded extension 21 by which it may be mounted in the harness frame member 10. The stud 20 has a recess 22 formed in one side thereof and adapted to receive the heddle

bar 12. The recess is slightly longer than the width of the bar 12 and the upper end wall 23 of the recess is undercut as shown in the drawing to assist in retaining the heddle bar 12 in the heddle bar post P.

A spring member 30 is formed from a blank 31 (shown in Fig. 6) and comprises an upwardly extending tongue 32 (Figs. 7 and 8) and a pair of side ears 33.

The ears 33 are spaced to receive the stud 20, as shown in Figs. 2 and 3, and the spring member 30 is firmly secured to the stud 20 in some convenient way, as by a cross-pin or rivet 35 inserted through holes 36 in the ears 33 and a hole 37 in the stud 20. A shoulder 38 on the stud 20 provides additional support for the spring member 30.

The upper end of the spring tongue 32 is offset inward and again outward to provide an inwardly projecting part 40 and an outwardly inclined extreme upper end portion 41.

With this construction, a heddle bar 12 can be readily inserted in a side recess 22 by pressing the bar 12 against the inclined end portion 41 and thus outwardly displacing the offset part 40 of the tongue 32 until the heddle bar is seated in the recess 22. The spring tongue 32 will then move yieldingly inward toward normal position, firmly pressing the part 40 against the heddle bar 12 and preventing accidental displacement of the bar from the recess.

As the pull of the heddles tends to move the bar 12 away from the harness frame member 10, the undercut upper end wall 23 tends to retain the heddle bar in the recess 22 and to prevent lateral displacement thereof.

From the foregoing description, it will be seen that we have provided a heddle bar post comprising two parts only, and furthermore that these two parts are firmly and permanently secured together and that there is no relative movement between the parts, except for the slight outward swinging movement of the tongue 32 to admit the heddle bar 12.

Our improved heddle bar post is thus very simple and economical to manufacture and entirely reliable and satisfactory when used for its intended purposes.

Having thus described our invention and the advantages thereof, we do not wish to be limited to the details herein disclosed, otherwise than as set forth in the claims, but what we claim is:

1. In a loom harness, a heddle bar post comprising a rigid stud having a side recess to receive a heddle bar, means by which said stud is

secured in the harness frame, and a retaining member having its lower part fixed on said stud and substantially immovable relative thereto and having a free resilient tongue partially overlying said side recess and effective to engage and yieldingly prevent accidental displacement of a heddle bar from said recess.

2. In a loom harness, a heddle bar post comprising a rigid stud having a side recess to receive a heddle bar, means by which said stud is secured in the harness frame, and a spring member having its lower part fixed to the lower part of said stud and substantially immovable relative thereto and having its free yielding upper end partially overlying said side recess and positioned to be yieldingly displaced outwardly by insertion of a heddle bar in said recess, and said free end of said spring member being thereafter effective to automatically return to holding position and

5 to yieldingly prevent accidental displacement of a heddle bar from said recess.

3. In a loom harness, a heddle bar post comprising a rigid stud having a side recess with an undercut outer end wall and adapted to receive a heddle bar, means by which said stud is secured in the harness frame, and a retaining member fixed to the lower part of said stud and having a free resilient upper end part thereof partially overlying said side recess and positioned to be yieldingly displaced outwardly by insertion of a heddle bar in said recess, said retaining member being thereafter effective to yieldingly prevent accidental displacement of a heddle bar from said recess, and said undercut end wall co-acting with said retaining member to prevent such displacement.

JOHN M. SAMPLE.

JOSEPH E. BLANCHARD.
